UNITED STATES PATENT OFFICE.

GEORGE LOUIS LANG, OF NEWARK, NEW JERSEY, ASSIGNEE TO SPLITDORF ELECTRICAL COMPANY, OF NEWARK, NEW JERSEY, A CORPORATION OF NEW JERSEY.

METHOD OF GENERATING IGNITION-CURRENTS FOR INTERNAL-COMBUSTION ENGINES AND APPARATUS THEREFOR.

1,233,587.

Specification of Letters Patent. Patented July 17, 1917.

Application filed August 31, 1916. Serial No. 117,918.

To all whom it may concern:

Be it known that I, GEORGE LOUIS LANG, a citizen of the United States, residing at Newark, in the county of Essex and State of New Jersey, have invented certain new and useful Improvements in Methods of Generating Ignition-Currents for Internal-Combustion Engines and Apparatus Therefor, of which the following is a specification, reference being had to the accompanying drawing.

This invention relates to a method of generating ignition currents for internal combustion engines, and particularly for starting the same. A suitable type of ignition dynamo is described, as commonly termed a "magneto". The invention has for its principal objects a system of spark production particularly suited to starting aeroplane engines; the production of a machine particularly applicable to the system, and the provision of special means for starting the engine directly from the magneto, thereby eliminating the use of batteries or auxiliary magnetos as heretofore employed for this purpose.

Another object is to provide a magneto adapted to furnish ignition current for the engine during the normal running thereof and yet have this same magneto with the addition of comparatively few parts arranged to generate a current with the engine at rest by revolving the generating winding.

Ancillary objects will hereafter more fully appear.

Referring to the accompanying drawings in which like numerals denote the same parts wherever they are shown, Figure 1, is a sectional view of a magneto embodying my invention. Fig. 2, a sectional view at right angles to Fig. 1, through the center of the machine, and Fig. 3, a diagram of the circuit connections.

The numeral 1, denotes the generating coils or windings of the magneto placed about a core 1^a provided with outwardly extending pole faces 1^b and 1^c, thereby forming a coil structure somewhat similar to the ordinary shuttle wound armature. This structure together with the casing 1^d is supported by shafts 1^e and 1^f, in bearings in the frame-work 23, 24 of the machine.

It is customary in a magneto of this type to provide primary and secondary windings,

and in the machine here described, one end of the primary winding may be connected to the framework 1^d of the coil structure, while the remaining end of the primary connects to the stem 2, passing through the shaft 1^f, but insulated therefrom. This stem serves to conduct the primary current to the insulated contact 3, of the primary or starting interrupter 15, and from there by means of conductor 4 to the insulated contact of the service interrupter 6, the insulated contact of which is connected to the post 5. The service interrupter is actuated by a cam 6^a mounted upon one end of the rotor shaft 6^b. As these interrupters may be of any suitable type, I do not describe the same in detail.

The numeral 7 denotes a contact member connecting from the secondary winding to the moving member 20 of the high tension distributor, it being understood that this distributor may be of any suitable type and that the moving member 21 is driven in synchronism with the rotor shaft 6^b, by means of the gear 7^a in the usual manner. This distributor may be for any number of cylinders.

8 is a gear, keyed to the shaft 1^f, and 9 is a gear meshed in gear 8 and keyed to the shaft 9^a, to which is also attached the starting handle 10. 11 denotes the driving gear of the magneto, which is meshed with a driving gear 12 on the engine. These gears 11 and 12, drive the rotor 13 of the magneto in synchronism with the engine 90 crank shaft, this rotor conducting flux to pole pieces 13^a, 13^b, of the field structure.

14 denotes the cam for the starting interrupter 15. 16 indicates a primary condenser, which may be carried within or upon the housing 1^d, so as to be rotatable therewith, or the condenser may be located elsewhere and connected in circuit as shown in Fig. 3.

All of the parts except the gear 9 and its associated shaft 9^a, may be supported upon a base 17 and inclosed within a suitable housing.

As the construction and operation of a magneto of this type is already known, I do not describe the same in further detail, but will now confine myself to a description of the features that are new.

The magneto being timed to the engine in the usual way and the rotatable coil struc-

ture being positioned as shown at Fig. 2, it is obvious that the windings are suitably positioned between the upper pole pieces 18 and 19 of the field structure to generate a current when magnetic flux is passed through the core 1^a, which occurs when the rotor 13 is revolved in the ordinary manner, it being understood that crank 10 is in a downward position as indicated by the dotted lines, Fig. 2. This not only properly positions the coil structure as shown in Fig. 2, but also holds the contacts of the starting interrupter 15 open, thereby permitting the service interrupter 6 to control the operation of the magneto.

The foregoing describes the normal running condition. To start the engine the same is turned over or "cranked" until the contacts of the service interrupter 6 are open, and rotor 13 occupies approximately the position shown in Fig. 2, then handle 10 is revolved in the proper direction, and through gears 8 and 9, the coil structure is revolved, thereby causing a reversal of flux through the core 1^a, and a generation of current in the windings. The high tension or secondary current flows by way of 7 to the moving member 20 of the distributor. As 20 must be connected to some one of the spark plug terminals or cables, a spark is produced at the plug diagrammatically indicated at 21, the circuit being completed through the frame of the engine and magneto.

It will be understood that with a magneto of the type shown, the rotor 13 has two prongs NN which contact with the N pole of the permanent magnet 22, and two prongs SS which contact with the S pole of the magnet and that when the engine is turned so that the service interrupter 6 is open, the rotor is in the proper position to conduct flux from the poles of the magnet to the poles 13^a, 13^b of the field structure, also 18 and 19, so that when the core 1^a is revolved in the manner just described, the flux through the same will be broken and reversed with each revolution thereof.

Upon the engine starting due to the operation of the coil structure, as just described, the handle 10 is immediately stopped in the position shown by the dotted lines Fig. 2, thereby opening the starting interrupter 15, which permits the service interrupter to control the output and permit the magneto to function in the normal manner. Owing to the fact that the distributor mechanism is driven in synchronism with the rotor 13, it is evident that the spark will be properly distributed to the several cylinders, whereas when starting, the rotor 13 being stationary and the coil structure only being revolved, the spark will be delivered continuously to one spark plug until the motor starts.

While I have shown one embodiment of

my invention, it is obvious that the details of same may be varied within wide limits without however departing from the appended claims, the arrangement here shown being obviously only one of many possible 70 embodiments thereof.

1. In an ignition dynamo, an exciting field structure, a coil structure, stationary pole pieces for said coil structure, means including a rotor to shift the flux from said field structure with respect to said pole pieces, and independent means for shifting the coil structure separately from said rotor with respect to said pole pieces.

2. In an ignition dynamo, an exciting field 80 structure, a coil structure, stationary pole pieces for said coil structure, means including a rotor to shift the flux from said field structure with respect to said pole pieces, and independent means for shifting the coil 85 structure separately from said rotor with respect to said pole pieces, said means including a shaft for said coil structure revolvably supported on said dynamo.

3. In an ignition dynamo, an exciting field 90 structure, a coil structure, stationary pole pieces for said coil structure, means including a rotor to shift the flux from said field structure with respect to said pole pieces, and independent means for shifting the coil 95 structure separately from said rotor with respect to said pole pieces, said means including a supporting shaft and handle whereby the same may be revolved.

4. In an ignition dynamo, an exciting field 100 structure, a coil structure, stationary pole pieces for said coil structure, means including a rotor to shift the flux from said field structure with respect to said pole pieces, means adjacent the sides of said exciting 105 field structure for supporting said flux shifting means, and means for revolvably supporting said coil structure whereby the same may be revolved independently of said flux shifting means to produce a current.

5. In an ignition dynamo, an exciting field structure, a coil structure, stationary pole pieces for said coil structure, means to shift the flux from said field structure with respect to said pole pieces, interrupter mechanism synchronously operated with said flux shifting means for timing purposes, independent means for shifting said coil structure with respect to the stationary pole pieces, and interrupter mechanism adapted 115 to be actuated by the shifting of said coil structure.

6. In an ignition dynamo, a field structure having two sets of poles, a rotor between one set of said poles, a coil structure between the remaining poles, and means for independently revolving said rotor and said coil structure whereby either may be used to generate a spark while the other remains at rest, substantially as described.

7. In an ignition dynamo, a field structure having two sets of poles, a rotor between one set of poles, a coil structure between the remaining poles, means for independently revolving said rotor and coil structure whereby either may be used to generate a spark while the other remains at rest, interrupter mechanism operated in synchronism with the movement of said rotor, and separate interrupter mechanism operated in synchronism with the movement of said coil structure.
8. In an ignition dynamo, a field structure having two sets of poles, a rotor between one set of poles, a coil structure between the remaining poles, means for independently revolving said rotor and coil structure whereby either may be used to generate a spark while the other remains at rest, interrupter mechanism operated in synchronism with the movement of said rotor, separate interrupter mechanism operated in synchronism with the movement of said coil structure, a distributor having a moving part driven in synchronism with said rotor and an electrical connection between said distributor and coil structure.
9. In an ignition dynamo, a field structure having two sets of poles, a rotor between one set of poles, a revoluble coil structure between the remaining poles, separate circuit interrupters operated in synchronism with said rotor and said revoluble coil structure, a distributor operated in synchronism with said rotor, an electrical connection between the moving part of said distributor and said coil structure, and a connection between said interrupters whereby the operation of either interrupter is dependent upon the position of the other, substantially as described.
10. In an ignition dynamo, a field structure having two sets of poles, a rotor between one set of poles, a revoluble coil structure between the remaining poles, a supporting shaft for said coil structure, an insulated lead passing through said shaft, interrupter mechanism connected to said lead, and means on said shaft whereby the same together with the parts connected thereto may be revolved to generate a current while the said rotor remains at rest, substantially as described.
11. In an ignition dynamo, a field structure, a rotor revoluble therein, a coil structure within the field structure and revoluble therein independently of said rotor, and a condenser electrically connected to said coil structure.
12. In an ignition dynamo, a field structure, a rotor revoluble therein, a coil structure within the field structure and revoluble therein independently of said rotor, and a condenser connected to said coil structure and movable therewith, substantially as described.
13. In an ignition dynamo, a field structure, a rotor revoluble therein, interrupter mechanism adapted to be operated in synchronism with said rotor, distributor mechanism adapted to be operated in synchronism with said rotor, a coil structure revoluble within said field structure, and mechanism for revolving said coil structure, said mechanism enabling the relative position of said coil structure to be determined, substantially as described.
14. In an ignition dynamo, a substantially U-shaped magnet, a field structure having two pairs of poles at right angles to the poles of said magnet, a rotor adapted to turn between one pair of said poles, a coil structure including windings and a core adapted to turn between the remaining poles, and means for driving said rotor and said last structure independently of each other.
15. The method of generating ignition current for internal combustion engines which consists in providing a primary magnetomotive force, shifting the flux due thereto in a symmetrical figure by means controlled by the movement of the engine, conducting the said flux through a normally stationary core carrying generating windings, and for starting purposes altering the direction of the flux flow through said core while the other parts remain at rest, substantially as described.
16. The herein described method of furnishing ignition currents for starting internal combustion engines which consists of providing a primary magnetomotive flux, providing a path for said flux through the core of a generating coil, shifting said core and coil in the flux path, interrupting the current so generated at its maximum peak for supplying starting sparks, stopping said generating coil in a predetermined position and continuing the flux flow therethrough by means positively driven by the normal running of the engine, said means serving also to distribute the current generated, substantially as described.

In testimony whereof I hereunto affix my signature in the presence of two witnesses.
